ATTORNEY

UNITED STATES PATENT OFFICE.

JAMES O. SPEAR, OF BALTIMORE, MARYLAND, ASSIGNOR TO THE DRESSING CABINET SUPPLY COMPANY OF BALTIMORE CITY, OF MARYLAND.

DESIGN FOR A TOILET CABINET-CASE.

SPECIFICATION forming part of Design No. 22,786, dated September 12, 1893.

Application filed August 11, 1893. Serial No. 482,944. Term of patent 3½ years.

To all whom it may concern:

Be it known that I, JAMES O. SPEAR, a citizen of the United States, residing at Baltimore, in the State of Maryland, have invented and produced a new and original Design for a Toilet Cabinet-Case, of which the following is a specification, reference being had to the accompanying drawing, showing a part thereof.

The drawing shows a front perspective view 10 of a toilet cabinet case having my design.

The case is rectangular in shape and the leading feature is the design of the front, which comprises a base portion in the form of a rectangular frame, A, longer in the horizontal direction than in the vertical direction; this is separated from the upper main portion which is in the form of a rectangular frame, B, whose sides are equal,—in other words the upper main frame, B, is square 20 while the base frame, A, is oblong in the hori-

zontal direction. The base frame has at each end a small rectangular raised panel, C, and a plain central space, D, between the said two panels. The upper square frame, B, has at and within each of its four corners a sunken 25 triangular panel, E, and at the center is a diamond-shaped panel, F. The four triangular corner panels and the central diamond-shaped panel, together, cover the entire front of the upper square frame, B. 30

What I claim is—

The design for a toilet cabinet case herein shown and described.

In testimony whereof I affix my signature in the presence of two witnesses.

JAMES O. SPEAR.
